(57) **CLAIM**

I claim the ornamental design for a tool grip, as shown and described.

DESCRIPTION

FIG. 1 is a right, front, top perspective view of a tool grip showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view of the tool grip, taken along line 8-8 in FIG. 4; and,

FIG. 9 is a right, front, bottom perspective view.

The broken lines in the drawings illustrate portions of the tool grip which form no part of the claimed design.
